Specification for Design.

Patented Mar. 17, 1914.

Application filed January 26, 1914. Serial No. 814,599. Term of patent 14 years.

To all whom it may concern:

Be it known that we, CLAYTON C. HARTING and THERON L. KNAPP, citizens of the United States, and residents of the city of Woodstock, in the county of McHenry and State of Illinois, have jointly invented a new, original, and ornamental Design for a Type-Writing-Machine Frame, of which the following is a specification, reference being had to the accompanying drawing, forming part hereof.

The figure is a perspective view of a typewriting machine frame, showing our novel design.

We claim:

The ornamental design for a typewriting machine frame, as shown.

CLAYTON C. HARTING.
THERON L. KNAPP.
